CLAIM

The ornamental design for a network terminal, as shown and described.

DESCRIPTION

FIG. 1 is a perspective view of a network terminal, showing our new design;

FIG. 2 is a front view of FIG. 1;

FIG. 3 is a rear view of FIG. 1;

FIG. 4 is a left side view of FIG. 1;

FIG. 5 is a left side view of FIG. 1;

FIG. 6 is a top view of FIG. 1;

FIG. 7 is a bottom view of FIG. 1; and,

FIG. 8 is another perspective view thereof, shown with environmental subject matter.

The broken lines in FIG. 8 showing the cylindrical pole depict environmental subject matter only and form no part of the claimed design.

The broken lines illustrating portions of a network terminal form no part of the claimed design. The claim is directed to the design shown in solid lines and shaded surfaces; all unshaded surfaces shown between the broken lines and solid lines form no part of the claimed design.
